(57) **CLAIM**

The ornamental design for a bicycle ramp as shown and described.

DESCRIPTION

FIG. 1 is a perspective view of a bicycle ramp according to the claimed design.

FIG. 2 is a front view of the bicycle ramp.

FIG. 3 is a rear view of the bicycle ramp.

FIG. 4 is a right side view of the bicycle ramp.

FIG. 5 is a left side view of the bicycle ramp.

FIG. 6 is a top view of the bicycle ramp.

FIG. 7 is a bottom view of the bicycle ramp; and,

FIG. 8 is a perspective view of the bicycle ramp in a condensed configuration.

The bicycle ramp is adjustable to the condensed configuration to reduce the spacing between the legs and the ramp surface.
